FOLDABLE CABINET

Walter K. Harris, Richmond, Va.

Application March 25, 1946, Serial No. 656,945

4 Claims. (Cl. 229—41)

1

My invention relates to cabinet structures, and particularly to those of a foldable type. It has for its object the production of a cabinet or other receptacle of the portable and folding type which may be quickly unpacked, erected, or again folded; which shall be light in weight; rigid when erected; inexpensive; and which shall be folded for packing in a small space. For the purpose of this application I have shown my invention as developed in a foldable wardrobe.

Figure 1 shows the erected wardrobe in perspective.

Figure 2 is a vertical section of the erected wardrobe.

Figure 3 is a vertical section of the wardrobe in the process of erection.

Figure 4 is a front elevation of the wardrobe with a part of the front cut away to show the interior.

Figure 5 shows the wardrobe in process of being folded.

Figure 6 shows the wardrobe folded.

Figure 7 is a cross section of the front and the door of the wardrobe.

Figure 8 is a partial cross section showing a socket for supporting a coat-hanger rod.

Figure 9 is a partial perspective of the bottom of the wardrobe showing the fastening of the bottom shelf.

Figure 10 is partial cross section showing the same fastening of the bottom shelf, in detail.

My foldable wardrobe may be made of any suitable thin material; metal or wood, plywood, paper, paper-board, fibre-board. I will describe the fibre-board construction.

In Figures 1, 2, 3, and 4 the wardrobe 2 consists of the side walls 4, 4; the back 6; the front 8, provided with an opening 10 for door 12 hinged to one side of opening 10; the hinged top 14; the hinged bottom 16; the hinged upper shelf 18; and the coat-hanger rod 20.

The back 6 extends above the other walls of the wardrobe to form a seat 22 for the flat spring 24, the purpose of which is to catch the free edge 26 of the hinged top 14, as seen in Figures 1 and 2. The top 14 is shown hinged on the front wall 8 of the wardrobe, at 25, opposite to the upwardly extended back 6 carrying the flat spring 24. Obviously the positions of the hinge and of the spring catch may be exchanged; the hinge being placed on the back 6 and the spring catch being placed on an upwardly extended front. As the hinged top 14 is swung down, its free edge 26 presses back the lower edge of the spring catch 24, and passes it; and the catch snaps back, and holds the free edge of the top 14 down, as shown in Figures 1 and 2. The top 14 has downwardly folded side-wings 28 which fit closely against the inside of the side walls 4, and at the same time

2

strengthen and stiffen the squared edges of the top 14.

When bending fibre-board on a line to form an angle or a hinge the bending may be helped by scoring the inside of the fibre-board on the bend line before attempting to make the bend.

The top 14 is made of two thicknesses; the lower one, 32 being integral with the wings 28 and the flat part of the top 32 is made by scoring and then bending the fibre-board as explained above. If the fibre-board is of heavy construction it may be thinned on the inside of the bend by a shallow knife-cut. As will be seen in Figures 1 and 2: an outer thickness 34 is cemented on top of the under thickness 32 to add strength and finish.

The upper shelf 18 is shown hinged on the inside of the front 8 at 36, as indicated by dotted lines. This shelf has a rear wing 38, and side wings 40 which are notched at 42 to engage and rest upon the coat-hanger 20 or its support 44. The said support is formed of a strip of light metal 46 bent to shape and passed through slots 48 cut in the side walls 4 (see Figures 2, 4, and 8).

The bottom 16, which forms a lower shelf, is shown hinged at 50 on the inside of the back 5. This bottom shelf has side wings 52 and a front wing 54 which is cut, as at 56 (Figure 10) to form a tongue 58 which, when the bottom is pressed down, and into place, enters slot 60, which is formed in a strip 62 cemented across the bottom edge of the front 8 below the door-opening 10. This construction of the bottom shelf 16, tongue 58, and strip 62 with slot 60 for receiving the tongue 58 adds greatly to the strength and stiffness of the structure when erected. The stiffness of the structure is also aided by the method by which the upper shelf 18 and the top 14 are hinged and are held in place.

The front 8, side walls 4, and back 6 may be formed separately if necessary, and be hinged together on their vertical edges; or they may be cut from one piece of fibre-board, and scored 45 and bent on lines to form the vertical corners of the structure. The top 14 may also be cut as an integral part of the front 8; later to be scored and bent to form the hinge 25. The joint between front and side or between back and side 50 is to be made permanent, by cementing, or by other means.

The door 12 is made of double thickness preferably; the inner thickness 64 fitting within the door opening 10; the outer one 66 overlapping 55 the opening at top, bottom, and on one side 68. The door is hinged to the front 8 on the opposite side 70. The opening 10 is cut to one side of the center of the front 8, so that the door when closed will be centrally located. Its hinged edge 70 60 does not overlap the opening, or only by very

little; the separation being closed by the fibre or cloth hinge which extends from top to bottom. The inner thickness 64 of this door may be actually a part of the front 8; being cut from the front around the top, bottom, and one side; the remaining side being scored and bent to form the hinge. As the door is opened and closed many times I prefer to reinforce the bent hinge with a strip of suitable fabric.

The door latch 72 (Figs. 1, 4, and 7) slides in a slot 74 formed between the door thicknesses 64 and 66. This slot can be made by forming it on the inner or on the outer thickness of the door; or it can be made by interposing between the inner thickness 64 and the outer thickness 66 and upper and a lower thickness of fibre-board, leaving the slot 72 between them, as indicated in Figure 7. The latch is bent at 76 to form a handle 78; and it is offset at its ends 80 and 82 so that it may overlap the front at the edges of the opening 10. When the door is closed (Figure 7) the overlapping of the latch ends 80 and 82 on the edges of the opening 10 greatly stiffen the front and door structure.

To fold the wardrobe: the spring catch 24 is pressed back, and the free edge 26 of the top 14 is released and raised. The wings 28 are then folded back, even with the top sheet 32. The upper shelf 18 is raised and is swung upward on its hinge 36; and its wings 38 and 40 are then spread even with the shelf itself. The bottom 16 is then raised on its hinge 50; and its wings and tongue 58 are spread even with the bottom itself. The rod 20 may be left in place, or it may be lifted out of its supports 44. Or one end of the rod may be left in place and the other end lifted from its support. The whole structure may then be folded, as shown in Figure 6. In Figure 5 it is shown half way folded. The shipping space required for one of the folded wardrobes is much less than that which would be required for the erected wardrobe, or for one of the non-folding type having the same holding capacity.

I have shown my invention developed in the form of a wardrobe or hanging closet. It can be developed in other forms—for instance as a book-case—by simply adding hinged shelves spaced apart far enough so that they can be folded up.

It will be noted that the top 14, bottom 16, and upper shelf 18 are not all hinged on the same wall of the cabinet. The hinged edges of the several parts are stiffer than their free edges; consequently placing these hinged edges on different walls of the structure add to its rigidity when erected. The lower portion of the structure is likely to be subjected to the greater torsional strains; and the method of hinging and latching the bottom 16 is an aid against these strains.

I claim:

1. A foldable cabinet having in combination four rectangular walls hinged together by vertical and parallel hinges and foldable together by closing two opposing hinges and opening the other two hinges; one of the rectangular walls being extended upward and higher than the other walls; a top member hinged to the wall opposite to the extended wall and adapted to swing down upon the adjacent walls and against the extended wall; and a spring catch secured on the extended wall and adapted to catch and to hold down the free edge of the top member against the wall extension,

2. A foldable cabinet having in combination four rectangular walls hinged together by vertical and parallel hinges and foldable together by closing two opposing hinges and opening the other two hinges; one of the rectangular walls extended its width upward and higher than the other walls; a rectangular top member hinged to the wall opposite to the extended wall and adapted to swing down upon the adjacent walls and against the width of the wall extension; a spring catch extending the width of the wall extension and secured to the extended wall and adapted to catch and to hold down along its length the adjacent edge of the top member as it is swung down upon the two adjacent walls.

3. A foldable cabinet having in combination four rectangular walls hinged together by vertical and parallel hinges and foldable together by closing two opposing hinges and opening the other two hinges; one of the rectangular walls extended its width upward and higher than the other walls; a rectangular top member hinged to the wall opposite to the extended wall and adapted to swing down upon the adjacent walls and against the extension of the other wall; and a resilient strip of material secured by its upper edge to and extending across the wall extension and with its lower edge standing out from the surface of the wall extension and adapted to be pressed back by the descending edge of the closing top member and to spring out over the said edge after it has passed.

4. In a foldable cabinet having in combination four rectangular walls hinged together by vertical and parallel hinges and foldable together by closing two opposing hinges and opening the other two opposing hinges; one of its walls extending its width upward and higher than the other walls; a rectangular top member hinged to the wall opposite to the extended wall and adapted to swing down upon the adjacent walls and against the extension of the other wall; a door hinged in an opening in one of the walls; stop means to prevent the door opening inwards of the cabinet; and a bar of a greater length than the width of the door-opening slidably mounted on and against the inner surface of the door so that one end may pass beyond the hinge of the door at all times and so that the other end is slidably behind the opposite door-jamb to lock the door and retractable from behind the door-jamb to free the door.
